WIRE-FORMING MACHINE

Andrew Max Zweyer, Los Angeles, Calif., assignor,
by mesne assignments, to Zig Zag Spring Co.,
a corporation of California

Application April 22, 1946, Serial No. 664,118

10 Claims. (Cl. 140—105)

1

This invention relates to wire-forming machines, and contemplates more specifically apparatus for imparting a tortuous contour to steel wire stock for subsequent tempering as a step in the manufacture of flat springs adapted particularly for use in cushion structures.

Springs of the type for the production of which the machine of the present invention is adapted are well known in the art. The wire stock of which such springs are composed is bent in the process of manufacture to form a series of uniform lateral offset curves or loops connected by straight, equi-spaced, usually parallel, reaches so as to delineate a symmetrical flat pattern with the loops lying in a common plane. In accordance with conventional utility of springs of this type, the ends thereof are equipped with brackets that are attached between suitable supports with the springs arcuately disposed in opposition to the load to be sustained. Variations in the weight or pressure applied to such a spring so arranged to receive the load from a direction extending in a plane through the terminals of the spring are resiliently compensated by the longitudinal expansion and contraction of the lateral offsets. Thus, a spring of this type is adapted to afford support for a cushion or the like over an area equal to its width and length with the entire load being absorbed between the ends and without any extension or contraction in the over-all length thereof.

However, the commercial manufacture of springs of this type involves numerous problems not encountered in the production of springs of any other form due to their essential tortuous contour. Heretofore in the art the only mechanism available for commercial manufacture of said springs was very complex, expensive, and relatively inflexible in its adaptation to manufacture of springs of different sizes.

It is accordingly a general object of the present invention to provide novel apparatus operable to form wire of the type above alluded to from steel spring wire stock fed continuously thereto so as to impart a flat, symmetrical winding contour to the wire, having substantially parallel reaches connected and equi-spaced apart by uniform loops adapted, when spring tempered, to resiliently sustain loads transversely applied.

More specifically, a principal object hereof is the provision of forming mechanism comprising a reciprocating table and an oscillator equipped with a pair of forming pins, the operation of the table and oscillator being synchronized to bend the wire alternately around the respective pins to a variable extent depending upon the resiliency

2

of the stock and the desired angle to be formed between the lateral offsets in the wire.

Another object is to provide an oscillator embodying self-feeding mechanism operable to draw stock from a source of continuous supply at a speed commensurate with the requirements of the forming apparatus, in combination with a composite roller drag to tension the stock and thereby assure uniformity in the results achieved by operation of the oscillator.

Another and highly important object is the provision of swinging arms alternately engageable with the wire as it is shaped by the forming mechanism to resist disturbance of the angular relationship between respective pre-formed lateral offsets in the wire incident to subsequent operations of the forming mechanism and further to insure the formation of straight reaches of wire between the loops therein by obviating any tendency of the wire to buckle or bow between the forming pins.

Another object is to provide a table and a roller superimposed thereon adapted to receive therebetween the wire as it leaves the forming mechanism to assure its continued movement toward a cutter or coiling apparatus, thereby preventing entanglement of the formed wire.

Numerous other objects and corresponding advantages of my invention, such for example as 30 simplicity of construction, continuous operation, ease of assembly, adjustment and replacement of worn parts, economy of manufacture and durability, will be apparent to those of skill in the art to which my invention appertains from an 35 examination of the following description read in the light of the accompanying drawings in which:

Fig. 1 is a plan view of a machine embodying my invention;

Fig. 2 is a plan view of the drive mechanism 40 for the unit located below the principal support therefor, and, schematically, the gear and chain mechanism above the support by which the various forming apparatus is directly actuated;

Fig. 3 is a side elevation of the assembly. 45 Fig. 4 is a sectional view taken on lines 4—4 of Figs. 1 and 3;

Figs. 5 to 9 inclusive are diagrammatic views 50 illustrating the successive steps, consecutively followed, during one-half cycle of operation of the oscillator and staying arms in the formation of a single lateral offset in the wire stock from which the spring is constructed.

Referring to the drawings in detail, the numerals of which indicate similar parts throughout the several views, 10 designates generally a bench having a circular top 11 supported by legs

12 comprising angle irons. The wire-forming apparatus hereinafter described is supported on top 11, and power for the unit is supplied by a motor 13 mounted on crossbeams 14 extending between legs 12 of the bench. A system of speed-reducing pulleys and belts transmits the power of motor 13 to the forming apparatus and comprises a small pulley 15 mounted on the upper end of the vertical shaft 16 of the motor. Laterally of motor 13 a shaft 17 is journaled in a bearing 18 suspended from the underside of top 11 for the rotatable support of a larger pulley 19 connected to pulley 15 by a belt 20. A smaller pulley 21 on the same shaft 17 is similarly connected to the larger pulley 22 carried by a shaft 23 journaled in a bearing 24 depending eccentrically from the underside of the circular table top 11. The shaft 23 projects upwardly through the table top and through a housing 25.

On the upper end of shaft 23 a drive sprocket 26 is mounted for engagement by a chain 27 adapted to transmit the motion of shaft 23 to a second sprocket 28, identical to sprocket 26, carried on the upper end of a vertical shaft 29 suitably journaled in a bearing generally indicated at 30. Mounted upon and projecting upwardly from sprocket 28 is an eccentric crank pin 31 to which a connecting rod 32 is pivotally attached. The opposite end of rod 32 is pivoted to a bracket 33 secured rigidly to the side of a guide table 34 supported at one end on a pin 35 journaled in the table top 11 whereby rotation of sprocket 28 is adapted to impart oscillatory motion to the table 34 throughout the operation of the unit.

The wire stock 36 from which the spring is to be formed is supplied from a storage drum (not shown) suitably journaled laterally of the bench 10, and extends through a wire straightener, hereinafter described, and on to table 34 over the pivoted end of the latter. The wire 36 is threaded through a double-roller guide 37 superimposed upon table 34 at the pivoted end of the latter. Intermediate the end of the table 34 and disposed normally in alignment with the tension drag and guide 37 is a second double-roller guide 38 mounted rigidly upon table 34 so as to oscillate therewith in response to the operation of the sprocket 28. The tension drag comprises a channeled block 39 supported on a post 40 above the bench at a level corresponding to that of the oscillating table 34. The upwardly projecting sides 41 of block 39 are disposed parallel with the wire stock 36 which extends therebetween from the storage drum to the guide 37 of table 34. At the outer end of block 39 and equi-spaced between its sides, a vertical pin 42 is mounted having a hole therethrough for the projection of the wire. On either side of the wire a roller bar 43 is arranged carrying a plurality of peripherally-grooved rollers 44 adapted to be urged into contact with opposite sides of the wire. The rollers 44 of one bar 43 are offset along the wire with respect to rollers 44 of the other bar 43, and both sets of rollers are moved against the wire by a plurality of screws 45 threaded through the corresponding sides of the channel block 39. The inner ends of screws 45 are accommodated in holes (not shown) in the sides of bars 43 so as to resist longitudinal movement of the latter while effectively controlling variation in the pressure of rollers 44 upon the wire incident to threaded adjustment of screws 45.

The oscillating table 34 is formed with a trans-

verse opening 46 intermediate its ends and adjacent and forward of guide 38 for the accommodation of an oscillator which comprises a circular block 47 rotatably mounted by suitable means upon a post 48 carried by bench 10. Encircling the bottom of the oscillator block 47 is a sprocket 49 engaged by a drive chain 50, opposite reaches of which encompass a larger sprocket 51 carried by a shaft 52 journaled in a suitable standard 53 supported by the bench top 11 directly below the extension of the wire 36 between the tension drag assembly and the oscillating table 34. Rotary oscillatory motion is thus transmitted to the oscillator block 47 through chain 50 and sprocket 49 from the drive sprocket 26 by means about to be described. A crank arm 54 is secured to the upper end of shaft 23, carrying a crank pin 55 to which a connecting rod 56 comprising a turnbuckle assembly is pivotally attached. The opposite end of the turnbuckle connecting rod assembly 56 is correspondingly pivoted to a crank pin 57 carried by a crank arm 58 mounted upon the upper end of shaft 52 to which the larger sprocket 51 is secured.

It will be observed that due to the differences in the degree of eccentricity of the respective crank pins 55 and 57 associated with sprockets 26 and 51, the latter sprocket is oscillated rotatably through a cycle of slightly less than one-fourth of a revolution with each revolution of the drive sprocket 26. Correspondingly, the relative sizes of sprockets 51 and 49 are such as to assure approximately a complete revolution of the oscillator block 47 with each arcuate stroke of the crank arm 58 associated with sprocket 51. The guide table 34 is adapted to shift laterally and return to its initial position with each revolution of the oscillator. With the crank pin 57 at one end of its range of movement, the connecting rod 32, pivoted to sprocket 28, is equi-distant the ends of its range of movement whereby the guide block 38 is positioned in alignment with the reach of wire stock 36 extending between the tension drag and the guide 37. A half revolution of the drive sprocket 26 transmits through chain 27 a like degree of motion to the sprocket 28 which is effective, first, to shift the guide 38 to an extreme lateral offset position in one direction and then return the same to an intermediate position in alignment with the direction of movement of the wire stock 36 as it is drawn from the storage drum. On the second half revolution of the drive sprocket 26 the direction of movement of sprocket 51 is reversed, correspondingly reversing the motion of the sprocket 49 and oscillator block 47 which returns a full revolution to its original position. During this operation the crank pin 31 moves through the opposite half of its complete cycle so as to first shift the oscillating table 34 to the opposite side of its normal position from that to which it was moved during the first half revolution of the drive sprocket 26, and then return the table to its initial position.

Mounted at diametrically opposite sides of the top of oscillator block 47 are a pair of forming pins 59 and 60 which project upwardly through the opening 46 in table 34 into the horizontal plane of the wire stock 36 extending between the rollers of the adjacent guide 38. With block 47 disposed at one end of its range of rotative movement, the forming pins 59 and 60 lie in a plane forming a 90° angle with the extension of the stock between the tension drag and guide 37. With the parts in the position shown in Fig. 1, the wire stock 36, projecting out of guide 38, is

bent around the outside of one of the pins 59 and extends diagonally between the pins to the opposite side of the other pin 60 around which it is wound and then bent in a straight reach 61 across the forward arcs of the pins.

Superimposed above the oscillating table 34 is a beam 62 supported at one end by a suitable standard 63 mounted upon the top 11 of bench 10 laterally of table 34. Depending rotatably from bearing housing 64 carried by the beam 62, is a pair of shafts 65 located at opposite sides and just out of the range of movement of the table 34. The lower end of each shaft 65 carries a sprocket 66 disposed in a plane below table 34 and in horizontal alignment with chain 50 with opposite reaches of which each sprocket 66 is operatively engaged. The sprockets 66 are identical in size and number of teeth to provide for their reciprocatory movement through slightly more than 180° with each full revolution of the oscillator block 47. A staying arm 67 is secured rigidly to and projects radially from each shaft 65 in a horizontal plane above the forming pins 59 and 60, carried by the oscillator block 47. Intermediate each arm 67 one end of a finger 68 is pivotally connected so as to overhang the outer end of the arm, which is cut away to accommodate a wire-engaging pin 69 depending from the end of the finger. Pin 69 projects downwardly into the horizontal plane of the wire, in contact with reach 61 to which it is moved upon alternate strokes of its arm 67. It will be understood that during actuation of the sprocket 51 and chain 50, the sprockets 66 are rotated simultaneously in the same direction, but as arms 67 project laterally for movement through opposed arcs, the pins 69 are swung in opposite directions so as to alternately shift the arms toward and away from the oscillator and the wire engaged with forming pins 59 and 60. The pressure exerted by the respective pins 69 of the staying arms 67 upon the wire coincident with the successive formation of the lateral offsets in the wire depends primarily upon the predetermined fixed relationship between the shafts 65 and arms 67. However, in order to permit critical variation of this factor upon which depends the angle formed between successive lateral reaches of the completed spring, as is hereinafter more in detail described, I provide an adjusting screw 70 threaded through the reduced outer end of each arm 67 to bear against the pin 69 depending from the outer end of the adjacent finger 68. By varying the extension of the screw 70 in each arm 67, the angle between the finger 68 thereof and arm may be altered so as to increase or decrease the extent to which the pin 69 overhangs the oscillator block 47 at the end of the forward movement of the arm. A retainer bar 71, secured by suitable means to the top of each arm 67, overhangs the adjacent finger 68 to frictionally engage the latter after proper adjustment of screw 70 is determined to resist pivotal displacement of the finger on the returned stroke of the arm. After passing through the oscillator, the formed wire is moved toward the outer end of table 34 where a channeled track 72 is provided to direct the wire from the assembly to a suitable spool or cutter (not shown). The channel 72 is supported at the level of table 34 by a bracket 73 mounted upon the bench top 11 and is spaced slightly from the outer end of table 34 so as not to interfere with the reciprocable movement of the latter. In order to assure the movement of the formed wire onto the channel 72, a roller 74 journalled between arms 75 pivoted to

the opposite sides of the adjacent end of channel 72 bears upon the work as it leaves the oscillator. A helical spring 76, connected between each arm 75 and the bench top 11 therebelow, normally exerts sufficient tension upon the roller assembly to assure the performance of its intended function while permitting the roller to be manually raised incident to pivoting of arms 75 so as to expedite the initial placement of the wire thereunder.

The operation of my invention is briefly described as follows: The wire is initially threaded through the hole in pin 42 between the sets of tension rollers 44 and between the rollers of the guides 37 and 38, and thence around the forming pins 59 and 60 of the oscillator and across the latter behind the pin 69 of the adjacent staying arm 67 with the end projecting onto the forward end of table 34 under the roller 74. The tension drag is then adjusted by manipulation of screws 45 to restrain, to the desired extent, the free movement of the stock therebetween. As the bars 43 to which the rollers 44 are journalled are movable laterally independent of one another and may be also tilted relative to the wire extending therebetween, it will be appreciated that the pressure imposed by any of rollers 44 upon the wire may not only be varied but also that the joint lateral movement of both bars 43 enables the critical alignment of the stock at the point of its extension from the tension drag with the guide 37.

Energization of motor 13 thereupon turns the drive sprocket 26 actuating the oscillator through the sprockets 51 and 49 and chain 50. Coincidentally, rotation of sprocket 28 and the oscillation of the table 34 is initiated. Reference is now made to Figs. 5 to 9 inclusive, wherein the forming operation is diagrammatically illustrated. Fig. 5 represents the more pertinent parts of the forming mechanism as shown in Fig. 1 in the position assumed at the conclusion of forming a lateral offset in the wire. It will be observed that the forming pin 59 is in a position maintaining the stock extending through the guide 38 in a taut condition and that the other forming pin 60 has just completed the formation of an offset loop in the wire. The pin 69 of the arm 67 is engaged with the transverse reach 61 of wire, leaving pin 60 so as to resist any tendency of this reach of wire to alleviate the distortion being effected by the forming pins. The initial movement of the drive sprocket 26 from this illustrated relationship of the parts (in a clockwise direction as seen in Fig. 1) begins the counter-clockwise rotation of the oscillator. The pin 69 of arm 67 is immediately shifted out of contact with the wire, and coincidentally tension upon the wire by pin 69 is relieved.

Pin 60, moving forwardly with a quarter turn of the oscillator toward its position as seen in Fig. 6, bears against the reach 61 of the wire heretofore engaged by the pin 69 of arm 67 so as to draw additional stock through guide 38. During this operation of the oscillator, the lateral movement of table 34 in the direction toward which the forming pin 59 is moved is begun, and coincidentally the other arm 67 begins its movement from its retracted position. These movements of the arms and table 34 are continued through the following quarter turn of the oscillator block, during which operation pin 60 moves out of engagement with the wire reach 61, and the pin 59 moves into contact with the back of the next lateral offset heretofore produced by pin 60. During the next quarter turn of the os-

7
cillator block 47, the pin 59 bears against the reach 71 of the wire 36 drawing additional stock through the guides 37 and 38 and contacts the wire at a rearward point. It will be noted from an examination of Fig. 5 that pin 59, being laterally disposed with respect to the line of supply of the wire stock 36, produces a bend in the wire at the mouth of guide 38. A feature of the invention resides in the proximity of the oscillator 47 to guide 38 whereby the distance between the bend in the wire, referred to, and the arc of movement of pin 60 is substantially equal to the distance to which the wire is moved in response to the urge of pin 59 during the third quarter of movement of the oscillator. This shifting of the wire brings the bend formed in a stock at the mouth of guide 38 into the arc of movement of pin 60. Thus, the coincident movement of the oscillator block 47 as above described, resulting in the contact of pin 60 against the bend in wire 36 as seen in Fig. 8, tends to increase the angle preformed in the stock at opposite sides of the bend. Attention is directed to the fact that as sprocket 28 will have traveled 90° by the time the oscillator reaches the position shown in Fig. 7, table 34 will be moving toward its intermediate or central position at the moment the forming pin 60 contacts the wire stock (Fig. 8) so as to bend the wire around pin 60 more effectively. As the oscillator moves through its final arc, i. e., from the position shown in Fig. 8 to that of Fig. 9, the forming pin 60 completes the offset as the guide 38 reaches its central position. During this operation the tendency of the forming pin 60 to shift laterally the formed wire in advance of the oscillator is compensated by the engagement of the pin 59 at the bend produced by pin 60 on the preceding operation so as to bend the reach rearwardly around the forward arc of pin 60.

During the final movement of the oscillator in the direction depicted diagrammatically in Figs. 5 to 9, inclusive, the staying arm 67 reaches a forward position whereat the pin 69 contacts the second reach 61 of the wire to maintain the parallel relationship of the lateral sections of the wire previously formed and prevents any tendency of the wire section to bow or buckle.

As the wire stock employed in manufacturing springs of the type contemplated possesses a quality of resilience, it is necessary to overbend each offset in the forming operation to a greater extent than desired in the completed spring. It will be observed that this result is achieved at the end of each operation of the oscillator (see Figs. 5 or 9), the reach 71 being bent rearwardly to an extent substantially equal to the diameter of pins 59 and 60, while the staying arms 67 alternately prevent disturbance of the angular relationship of the offset formed on the preceding operation. As the staying arm moves out of contact with the latter reach of the wire, the resilience of the stock tends to partially straighten the bend formed around the forming pin. By proper adjustment of the parts which must be determined in accordance with the resilience of the wire stock employed, each lateral reach assumes a parallel relationship with those previously formed and extends at right angles to the longitudinal axis of the spring, as illustrated. While the oscillator, as its operation is above described, makes a full revolution in each direction, the resilience of the work may necessitate either a greater or lesser degree of movement in order to produce a spring of the form depicted.

It will be appreciated that variation in the degree of rotation of the oscillator will also alter the contour of the springs produced from stock of the same size and quality, e. g., by reducing the movement of the oscillator, a more loose winding in the completed article is effected. The extent of this movement of the oscillator is controlled by adjustment of the turnbuckle connecting rod 56 in a conventional manner which, as will be obvious, increases or decreases the throw of the crank. Where adjustment of the turnbuckle is made in order to vary the angle between the adjoining offset reaches of the formed spring, corresponding adjustment of the screws 70 is required so as to assure the maintenance of the angle of each lateral offset during the formation of the next succeeding offset.

While I have shown and described but one embodiment of my invention, it will be apparent to those of skill in the art to which my invention appertains that numerous changes in size, design, shape and number of the various parts may be made, without departing from the spirit of my invention as defined in the appended claims.

What I claim and desire to secure by Letters Patent is:

1. In wire-forming apparatus of the character described, a rotatable oscillator, a pair of forming pins carried by said oscillator equi-spaced from opposite sides of the axis of said oscillator and movable arcuately with the latter, means to direct wire to be shaped into engagement with said forming pins, means to rotatably oscillate said oscillator shifting said pins to bend the wire over said pins alternately in opposite directions and thereby form a series of lateral offsets in the wire, and staying elements alternately engageable with successive lateral offsets respectively in the wire during the formation of succeeding offsets.
2. In wire-forming apparatus of the character described, a support, an oscillator block pivoted to said support, a pair of forming pins mounted upon said block eccentrically with respect to the point of pivoting of the latter, means to direct wire from a source of supply to said forming pins, means to oscillate said block to swing said pins alternately against said stock at successive points along its length to form a plurality of lateral offsets in said wire, and a pair of staying arm assemblies alternately engageable with the lateral offsets formed in the wire to resist deformation of the relationship between said offsets during the shaping of following reaches of the wire.
3. In a wire-forming apparatus of the character described, a pivoted table, means carried by said table to guide wire stock thereover, an oscillator carrying a pair of forming pins projecting into the plane of said wire adjacent said table to alternately engage and bend said stock, means to actuate said oscillator, and means to shift said guide means and table in directions opposite to the directions of movement of said forming pins, respectively, while the latter are bending said wire.
4. In wire-forming apparatus of the character described, a support, a wire straightening and tensioning device mounted on said support, a table pivoted on said support, a pair of guides carried by said table normally aligned with said wire straightening and tensioning device to receive and direct wire stock passing through the latter, a forming block rotatably mounted on said support adjacent said table carrying a pair of eccentric forming pins projecting into the

plane of the reach of said wire extending out of said guides, said pins being disposed at diametrically opposite sides of, and equi-spaced from, the axis of said block, and means to turn said block with the wire stock engaged with the pins thereof and to coincidentally shift said table so as to swing one of said guides and one of said pins against the stock in one direction while swinging the other of said pins against the stock in the opposite direction.

5. In wire-forming apparatus of the character described, a support, a wire straightening and tensioning device mounted on said support, a table pivoted on said support, a pair of guides carried by said table normally aligned with said wire straightening and tensioning device to receive and direct wire stock passing through the latter, a forming block rotatably mounted on said support adjacent said table carrying a pair of eccentric forming pins projecting into the plane of the reach of said wire extending out of said guides, said pins being disposed at diametrically opposite sides of, and equi-spaced from, the axis of said block, means to turn said block with the wire stock engaged with the pins thereof and to coincidentally shift said table so as to swing one of said guides and one of said pins against the stock in one direction while swinging the other of said pins against the stock in the opposite direction, and an arm pivoted to said support to engage said stock during and incident to the operation of said forming block and table to resist deformation of wire extending from the block at the opposite side of the latter from said guides.

6. In a wire-forming apparatus of the character described, a block having a pair of pins projecting therefrom in parallel relationship with the axis of the block, means to direct wire stock to be formed over said block between said pins, means to turn said block upon its axis, shifting one of said pins into engagement with one reach of the wire stock to advance said stock a predetermined distance over said block and move the other of said pins into engagement with a different reach of said stock to bend the latter around the first-mentioned pin.

7. In a wire-forming apparatus of the character described, a block having a pair of pins projecting therefrom in parallel relationship with the axis of the block, means to direct wire stock to be formed over said block between said pins, means to turn said block upon its axis, shifting one of said pins into engagement with one reach of the wire stock to advance said stock a predetermined distance over said block and move the other of said pins into engagement with a different reach of said stock to bend the latter around the first-mentioned pin, and means to reverse the direction of said movement of said block to disengage said pins from the respective reaches of the stock last engaged.

8. A wire-forming machine comprising an oscillator having a pair of spaced bending pins thereon, means for rotatably oscillating the oscillator about an axis between the bending pins through approximately 360°, means for feeding wire to be bent toward the oscillator so as to be engaged by the bending pins and bent thereby laterally into zigzag form, and restraining arms mounted for oscillatory movement about axes parallel to the axis of oscillation of the oscillator and positioned laterally of the path of movement of the wire, each arm carrying a restraining pin swingable toward the axis of oscillation of the

oscillator to engage a portion of laterally bent wire behind the bending pins and extending between the bending pins, and means for oscillating said restraining arms alternately in timed relation to the oscillator.

9. A wire-forming machine comprising an oscillator having a pair of spaced bending pins thereon and oscillatable about an axis between the pins, means for feeding wire to be bent toward the oscillator, means for oscillating the oscillator through approximately 360° with each oscillation terminating in a position wherein the pins are on opposite sides of the direction of movement of the wire, the wire feeding means including means in advance of the oscillator oscillatable across the direction of movement of the wire for swinging the wire laterally, means for oscillating the last-mentioned means in timed relation to the oscillator, restraining arms pivotally supported for oscillatory movement about axes laterally with respect to the said means and oscillator, said restraining arms carrying restraining pins engageable with that portion of bent wire that is immediately behind both bending pins on the oscillator at the end of an oscillation, and means for oscillating the restraining arms alternately and in timed relation to the oscillator.

10. A wire-forming machine comprising an oscillator having a pair of spaced bending pins thereon and oscillatable about an axis between the pins, means for feeding wire to be bent toward the oscillator, means for oscillating the oscillator through approximately 360° with each oscillation terminating in a position wherein the pins are on opposite sides of the direction of movement of the wire, the wire feeding means including means in advance of the oscillator oscillatable across the direction of movement of the wire for swinging the wire laterally, means for oscillating the last-mentioned means in timed relation to the oscillator in sympathy with the direction of oscillation of the oscillator during part of each oscillation but in opposition thereto during the remainder of each oscillation, restraining arms pivotally supported for oscillatory movement about axes laterally with respect to the said means and oscillator, said restraining arms carrying restraining pins engageable with that portion of bent wire that is immediately behind both bending pins on the oscillator at the end of an oscillation, and means for oscillating the restraining arms alternately and in timed relation to the oscillator.
